UNITED STATES PATENT OFFICE.

RAYMOND E. CRANE, OF CAMERON, WEST VIRGINIA.

DESIGN FOR A WATER-TANK.

41,220.

Specification for Design.

Patented Mar. 7, 1911.

Application filed November 21, 1908. Serial No. 463,929. Term of patent 14 years.

To all whom it may concern:

Be it known that I, RAYMOND E. CRANE, a citizen of the United States, residing at Cameron, in the county of Marshall and State of West Virginia, have invented a new, original, and ornamental Design for Water-Tanks, of which the following is a specification.

Reference is to be had to the accompanying drawing, forming a part hereof, wherein the single figure is a front perspective view of a water tank embodying my new design.

The essential features of the design are

the octagonal shape of the tank-body, a front wall integral with the body, an integral rear wall, and an opening in the top wall.

I claim:

The ornamental design for a water tank, as shown and described.

In testimony whereof I affix my signature in presence of two witnesses.

R. E. CRANE.

Witnesses:

G. E. CONAWAY,
NETTIE MCCUSKEY.

Copies of this design may be obtained for five cents each, by addressing the "Commissioner of Patents, Washington, D. C."
